UNITED STATES PATENT OFFICE.

WILLIAM D. SKIDMORE, OF PELHAM, NEW YORK.

DUMPING-CAR.

1,127,929.

Specification of Letters Patent.

Patented Feb. 9, 1915.

Application filed April 9, 1914. Serial No. 330,745.

To all whom it may concern:

Be it known that I, WILLIAM D. SKIDMORE, a citizen of the United States, and a resident of Pelham, Westchester county, State of New York, have invented certain new and useful Improvements in Dumping-Cars, of which the following is a specification.

My invention relates to railroad cars, more particularly to that class of cars known as dumping cars, such as are used, for instance, in railroad construction, for conveying ballast, filling material and the like to such places as the same may be needed, and dumping the same upon or at the side of the right of way; but it will be readily understood that cars constructed according to my invention may be used for other purposes as well as those above specified.

The object of my invention is to provide a car which shall be simple in construction and at the same time efficient and easy of operation, and which shall be adapted to dump its load either quickly and all at one time, or slowly and at a predetermined rate of discharge, and in which the adjustment of the mechanism so as to regulate the rate of discharge may be easily and accurately effected.

The invention consists in the novel construction, arrangement and combination of various devices and parts, as shown in the accompanying drawings, and hereinafter particularly described.

In the accompanying drawings, Figure 1 is a side elevation of the end portion of a car constructed according to my invention. Fig. 2 is an end elevation of a car constructed according to my invention, showing the same loaded and in its normal erect or carrying position. Fig. 3 is a transverse vertical section through a portion of the car, in its normal position. Fig. 4 is a similar view, certain portions being broken away, showing the car in its wide open position for dumping at the side of the track. Fig. 5 is a transverse vertical section of one side of the car, showing the same arranged for dumping on the track between the wheels of the car. Figs. 6 and 6^a are detail views hereafter further described. Fig. 7 is a detail elevation of the drums upon which the controlling chains are wound. Fig. 8 is a detail view of the controlling mechanism. Figs. 9 and 10 are re-

spectively front and side views of the air cylinder. Fig. 11 is a cross-sectional view through the cylinder. Fig. 12 is a detail view of a channel-iron more specifically referred to in the specification.

In carrying my invention into effect, I provide for the lower part of the car a running gear of the common or any suitable form of construction, comprising the necessary sills, bolsters or analogous members, mounted upon bogie trucks provided with journal-boxes forming the bearings for the ends of the axles, and supported by and secured to the running gear in any suitable manner are end members 12 and a bottom frame 14.

Referring particularly now to Figs. 3, 4 and 5, it will be seen that securely attached to the end frame members 12 and extending longitudinally of the car body on each side of the car, are channel-irons 16, to which are secured members 17, extending in a slanting direction downward and inward. These members 17 are rigidly secured, and do not change their position, but they bear swinging members 19 pivotally secured thereto by hinges 18. Extending upward from the bottom frame 14 is a bracket 22, and pivotally attached at 21 to this bracket are swinging members 20.

The parts above described form the carrying body of the car, and they are shown in Fig. 3 in a closed or carrying position, in Fig. 4 in a wide open position adapted to deliver the load at the side of the track, and in Fig. 5 in position to deliver the load on the track between the wheels.

When the car body is in the closed or carrying position shown in Fig. 3, the outer edges of the members 20 are supported by legs 23, (diagrammatically shown in Figs. 4 and 5) pivotally secured thereto by their upper ends. The lower ends of the legs 23 bear normally upon rollers 24 journaled in brackets upon a channel-iron 25. This construction is shown in detail on an enlarged scale in Figs. 6 and 6^a. The channel-iron 25 is supported on wheels 25^a which run upon a track-way 25^b. The channel-iron 25 and the track-way 25^b are provided with openings 25^c (see Fig. 12) through which the leg 23 may drop down when the channel-iron 25 is drawn toward the right of Fig. 6^a, thus allowing the parts to fall into the position shown in the dotted lines in Fig. 6. Levers 65 are provided for operat-

ing the channel-irons, shown in Fig. 1, and on an enlarged scale in Figs. 9 and 10. The member 20 is also supported by the link 29, the lower end of which is pivotally secured at 28 to the said member near its outer edge, and the upper end of which is secured to the chain 31 which passes over pulleys 35 and around drums 37 on the shaft 36.

10 The lower edge of the swinging member 19, when in the closed position shown in Fig. 3, is supported upon the upper or outer edge of the member 20. It is also supported by the link 27, the lower end 15 of which is pivotally secured at 26 to the member 19, and the upper end of

which is pivotally secured at 30 to the upper end of the member 29 and to the chain 31. It is obvious that the shaft 36 20 is rotated so as to wind the chain 31 thereon, the links 27 and 29 are drawn up and with them the upper and lower edges respectively of the members 20 and 19, as shown in Fig. 3, but when the chain is partially or completely unwound the parts assume the position of Fig. 5 or 4 as the case may be.

Pivots secured to the frame at 34 is a member 33. When the car is in a position for dumping at the side of the track the 30 member 33 is placed in the position shown in Fig. 4, but when it is desired to dump on the track between the rails the member 33 is placed in the position shown in Fig. 5. When the car is in the closed or carrying 35 position the member 33 may lie either way. This member 33 is manipulated by hand or in any suitable manner. It will of course be understood that these various parts above described are duplicated on the two sides of 40 the car.

When it is desired to dump in the track between the rails it is of course necessary to prevent the swinging member 19 from swinging too far outward, and it is also 45 desirable to provide means for holding the swinging member 19 in its extreme outward position (as shown in Fig. 4) when the dumping is at the side of the track. These results are obtained by means of the mechanism now to be described.

Pivots attached to the frame of the car, one on each side, are levers 70, (see Figs. 2-5) which normally tend to swing down by their own weight, but which may 55 be secured in the elevated position by catches 71 (see Fig. 2). Rigidly secured to these levers, at their inner or pivoted ends, are cross-bars 72, to the ends of which are secured links 73 and 74 respectively.

60 The lower one of these links, designated 74, has its lower end pivotally secured to an arm or block 76, pivotally secured to the frame at 75. The upper link 73 leads to one

short link 79 which is pivotally secured to a swinging block or stop 80, near one end thereof, the other end of said block 80 being pivotally secured at 81 to the frame. It will be obvious from an inspection of Figs. 70 2, 3, 4 and 5, that when the lever 70 is lowered and the parts are in position shown in Fig. 4, the arm or block 76 bears against the links 27 and 29 and prevents them from buckling and thereby upholds the swinging 75 member 19, but that when the lever 70 is raised and the parts are in the position shown in Fig. 5, the block 80 bears against the joint of the links 27 and 29 and holds them in the position shown in said Fig. 5 80

and thereby prevents the swinging member

19 from swinging farther outward.

The operations of opening the sides of a car constructed according to my invention, so as to discharge the load, and of closing 85 the same after the load is discharged, may be performed either by hand or by employing the compressed air from the air brake supply. When hand power is employed, it is applied to the shaft 36 in any suitable manner, as for instance, by means of a crank or similar device applied to the end of the said shaft, which may be square-ended for such purpose, and by means of which the shaft 36 may be rotated and the chain 31 90 95 wound up and the links 27 and 29 raised. During this operation the shaft is held against backward rotation by a pawl 39 (see Fig. 8) which engages with a ratchet 120 which is fast on the shaft 36. This 100 pawl forms part of a lever 41, pivotally secured to the frame at 101. The construction of this pawl and the devices immediately related thereto is shown in detail in Fig. 8. The lever 41 is pivoted to the end 105 of the car body at 101, and may be locked in the position shown in the drawing by means of the pin 130, which passes through a perforation in the said lever 41 and a corresponding perforation in the member 132, which is secured to the end of the car body. Pivoted to this lever 41 at 105 is a lever 102, 110 normally held in the position shown in the drawings by the spring 103. Pivotally secured to this lever at 104 is a rod 106, the 115 other end of which is pivotally secured at 107 to a sliding member 108, provided at its other end with a projection 135. This member 108 is slidably secured to the rod 41 by means of a sleeve 109, rigidly mounted 120 on the said rod 41. Also pivoted at 101 is an L-shaped lever 110, having its movement limited by the guide 111, and provided at one end with a notch adapted to be engaged by the tooth 135. To the other end of this 125 lever 110 is pivoted the pawl 39, as shown at 112, a portion of said pawl near the outer end thereof resting upon the stop 113

- until it strikes against the stop 133. The lever 102 is then moved against the pressure of the spring 103, thus disengaging the tooth 135 from the recess in the lever 110.
- 5 The pressure of the ratchet wheel against the toe of the pawl 39 forces the same upward, the lower end of the lever 110 moving to its extreme left hand position, thus allowing the free rotation of the ratchet 120.
- 10 When air is used for operating the mechanism, it is applied by means of the devices now to be described. Suitably secured, in a vertical position, on the end platform of the car is an air cylinder 49 (see Fig. 2)
- 15 which is connected with a compressed air supply source. In this cylinder operates a piston (not shown) to which is connected a piston-rod 48. Referring now to Fig. 9, (which is an enlargement of a portion of
- 20 Fig. 2) it will be seen that the piston-rod 48 has one side formed into a rack. This rack is intended to operate a pinion 47 being guided or steadied by the roller 90 (best shown in Fig. 7, which is a side elevation,
- 25 looking from the left, of the portion of Fig. 2 just above the cylinder 49) the said pinion 47 being fast on a windlass shaft 91 which also bears winding drums 92. Attached to these drums and adapted to be
- 30 wound up thereon are chains 93 (see Fig. 2) the other ends of which are secured to the winding drums 94 on the shaft 36. (See Figs. 1 and 7.) Since this same shaft 36 also bears the winding drums 37 and upon
- 35 which are wound the chains 31, unwinding the chains 31 on the drums 37 winds up the chains 93 on the drums 94 and vice versa. A guide roller 54 (see Figs. 9 and 10) is provided for directing and steadyng the
- 40 movement of the piston 48. On the piston rod 48, just below the guide roller 54 but on the forward side of the piston rod, is a lug or toe 50, which operates the bar 51 when the piston is raised. Connected to the
- 45 ends of this bar 51 are links 57 (see Figs. 9 and 10) which are connected to the forward ends of bell-crank levers 59, the other ends of which are operatively connected to the channel-irons 25 heretofore described.
- 50 The operation of my invention is as follows: Suppose that it is desired to dump by hand, and in the middle of the track, between the rails; the members 33 are swung into the positions shown in Fig. 5,
- 55 and the levers 70 (which normally when the car is closed lie in the position shown in Fig. 3) are swung upward. The levers 65 are then operated, which draws the channel-irons 25 out and permits the swinging
- 60 side members 19 and 20 to drop into the position shown in Fig. 5 and thus permit the load to discharge. After the car has been emptied of its contents, cranks are applied to the square ends of the shaft 36 and
- 65 by rotating the same the chains 31 are wound up and the swinging members are replaced into the position shown in Figs. 2 and 3, whereupon the levers 70 are elevated and secured by the catches 71.
- Suppose it is desired to dump outside of the track, on both sides. In that case the swinging members 33 are placed in position shown in Figs. 3 and 4, and the channel-irons 25 withdrawn as before, whereupon the members 19 and 20 swing outward to the full extent, as shown in Fig. 4, and are held there by the operation of the block 75 against the links 27 and 29. After the discharge the swinging members 19 are replaced as before described, the levers 70 being first elevated so as to withdraw the blocks 75 and permit the links 27 and 29 to be moved, and the channel-irons 25 are pushed back into their supporting position.
- If it be desired to dump on one side of the track only, the operation is the same, except that the parts on the corresponding side of the car only are operated.
- When the dumping is to be done by power, the opening and closing of the sides are performed by admitting air to the cylinder 49. If air is admitted below the piston, the rod 48 is moved upward, and by means of its rack operates the pinion 47 which unwinds the chains 93 from the drums 92, and allows the same to be wound up upon the drums 94, thus allowing the chains 31 to unwind from the drums 37. The levers 70 must of course first be released. To elevate the sides, air is admitted above the piston, moving the rod and rack downward, and operating the parts in the contrary manner to that just described. The determination of the load to the middle or one or both sides of the track as the case may be is accomplished in substantially the same way as is done when the load is dumped by hand, as has been already described.
- Having thus described my invention, what I claim as new and desire to secure by Letters Patent is as follows:
1. A dumping car, comprising running gear, end bdy members, a movable member suspended from the upper side of the car, a movable member secured to the lower part of the car near the middle line, a movable member secured to the lower part of the car near the side, and means for operating said movable members, comprising a rotatable shaft provided with a winding drum, a chain secured to a movable member and adapted to be wound around said drum, a ratchet wheel on said rotatable shaft, a pawl adapted to engage with said ratchet, and means for disengaging said pawl from said ratchet.
2. A dumping car, comprising running gear, end body members, a movable member suspended from the upper side of the car,

a movable member secured to the lower part of the car near the middle line, a movable member secured to the lower part of the car near the side, and means for operating said 5 movable members, comprising a link secured to a movable member, a chain secured to the other end of said link, a rotatable shaft provided with a winding drum adapted to receive the other end of said chain, a ratchet 10 wheel on said rotatable shaft, a pawl adapted to engage with said ratchet, and means for disengaging said pawl from said ratchet.

3. A dumping car, comprising running gear, end body members, a movable member 15 suspended from the upper side of the car, a movable member secured to the lower part of the car near the middle line, a movable member secured to the lower part of the car near the side, and means for operating 20 said movable side members, comprising a link secured to said first named movable member, a link secured to said second named movable member, the outer ends of said links being pivotally secured together, 25 a chain secured to said links at their point of attachment to each other, a rotatable shaft provided with a winding drum adapted to receive the other end of said chain, a ratchet wheel on said rotatable shaft, a 30 pawl adapted to engage with said ratchet, and means adapted to disengage said pawl from said ratchet.

4. A dumping car, comprising running gear, end bdy members, a movable member 35 suspended from the upper side of the said car, a movable member secured to the lower part of said car near the middle line, a movable member secured to the lower part of the car near the side, means for holding 40 said movable members in their closed position, means for operating said movable members, and means for holding said movable members in position for dumping the contents of the said car at the side of the 45 road-bed, comprising a lever pivotally fulcrumed in the upper part of said car body, a link secured to the other end of said lever, and a swinging stop pivcted to the end of the said car body, and having one end there- 50 of secured to the other end of said link.

5. A dumping car, comprising running gear, end body members, a movable member suspended from the upper side of the car, a movable member secured to the lower part 55 of the car near the middle line, a movable member secured to the lower part of the car near the side, means for operating said movable side members, comprising a link secured to said first named movable member, a link secured to said second named movable member, the other ends of said links being pivotally secured together, a chain secured to said links at their point of attachment to each other, a rotatable shaft provided with a winding drum adapted to re- 60

ceive the other end of said chain, a ratchet wheel on said rotatable shaft, a pawl adapted to engage with said ratchet, and means adapted to disengage said pawl from said ratchet; and means for holding said movable members in position for dumping the contents of said car at the side of the road-bed, said means comprising a lever pivotally fulcrumed in the upper part of said car body and provided at one end with a handle, a link secured to the other end of said lever, and a swinging stop pivoted to the end of the car body, having one end thereof secured to the last named link, and having its other end adapted to bear against one 80 of said first named links.

6. A dumping car, comprising running gear, end body members, a movable member suspended from the upper side of the said car, a movable member secured to the lower part of said car near the middle line, a movable member secured to the lower part of said car near the side, and means for holding said movable members in position for dumping the contents of said car between the rails, said means comprising a lever pivoted to the upper side of the said car, a link pivoted to the other end of said lever, a bell-crank lever pivoted to the end of the said car, one arm of said bell-crank lever being pivoted to the other end of said link, a second link pivoted to the other arm of said bell-crank lever, a stop lever fulcrumed on the end of said car body, the other end of said second named link being 95 pivoted to said stop lever.

7. A dumping car, comprising running gear, end body members, a movable member suspended from the upper side of the said car, a movable member secured to the lower part of said car near the middle line, a movable member pivotally secured to the lower part of the car near the side, means for operating said movable members, said means comprising a link secured to said first-named movable member, a link secured to said second named movable member, the other ends of said links being pivotally secured together, a chain secured to said links at their point of attachment to each other, a rotatable shaft provided with winding drum adapted to receive the other end of the said chain, a ratchet wheel on said rotatable shaft, a pawl adapted to engage with said ratchet, and means adapted to disengage said pawl from said ratchet; and means for holding the said movable members in position for dumping the contents of the said car between the rails, said means comprising a lever pivoted to the upper side of the said car, and provided with a handle at one end thereof, a link pivoted to the other end of said lever, a bell-crank lever fulcrumed to the end of said car, one arm of said bell-crank lever being pivoted to said 125

third named link, a fourth link pivoted to the other arm of said bell-crank lever and a stop lever pivoted to the end of said car and having pivoted thereto the other end of said 5 fourth named link, said stop lever being adapted to bear against one of said first named links:

8. A dumping car comprising running gear, end body members, a movable member 10 suspended from the upper side of the car, a movable member secured to the lower part of the car near the side, a movable member secured to the lower part of the car near the middle line, a supporting leg for said last 15 named movable member, a means adapted to support the lower end of said supporting leg, said means being provided with a perforation through which said leg is adapted to pass when said last named swinging 20 member is opened.

9. A dumping car, comprising running gear, end body members, a movable member suspended from the upper side of the car, a movable member secured to the lower part 25 of the car near the side, a movable member secured to the lower part of the car near the middle line, a supporting leg for said last-named movable member, a channel iron adapted to support the lower end of said 30 supporting leg, a track-way on which said channel iron is adapted to run, an opening in said trackway, and an opening in said channel iron, said supporting leg being adapted to pass through said openings when 35 said channel iron is in such a position that the said openings coincide.

10. A dumping car, comprising running gear, end body members, a movable member suspended from the upper side of the car, 40 a movable member pivotally secured to the lower part of said car near the side, a movable member secured to the lower part of said car near the middle line, a supporting leg for said last-named movable member, 45 and a slidable channel iron having mounted thereon a roller, said roller being adapted when said channel iron is in one position to support the bottom of said supporting leg.

11. A dumping car, comprising running gear, end body members, a movable member suspended from the upper side of the car, a movable member pivotally secured to the lower part of the car near the side, a movable member secured to the lower part of 55 said car near the middle line, a supporting leg for said last-named movable member, a slidable channel iron adapted to support said supporting leg, and a lever adapted to move said channel iron.

60 12. A dumping car, comprising running gear, end body members, a movable member suspended from the upper side of the car, a movable member pivotally secured to the lower part of the car near the middle line, a movable side member 65

pivots secured to the lower part of the car near the side, and means for operating the said movable side members, comprising a chain secured to a movable member, a rotatable shaft, provided with a plurality of winding-drums, a chain secured to a movable member and adapted to be wound upon one of said drums, a second rotatable shaft provided with a winding drum, and a chain one end of which is adapted to be wound upon the drum upon said last-named shaft and the other end of which is adapted to be wound upon a drum upon said first-named shaft.

13. A dumping car, comprising running gear, end body members, a movable member suspended from the upper side of the car, a movable member secured to the lower part of the car near the middle line thereof, a movable member secured to the lower part 80 of the car near the side, means for operating said movable members, comprising a chain secured to a movable member, a rotatable shaft provided with a plurality of winding drums, a chain secured to a movable member and adapted to be wound upon one of said drums, a second rotatable shaft provided with a winding drum, and a chain one end of which is adapted to be wound upon said drum upon said last named shaft 90 and the other end of which is adapted to be wound upon a drum upon said first named shaft; and a piston operated by compressed air, or the like, and operatively connected with said second named rotatable shaft. 95

14. A dumping car, comprising running gear, end body members, a movable member suspended from the upper side of the car, a movable member secured to the lower part of the car near the middle line thereof, a movable member secured to the lower part of the car near the side, means for operating the said movable members, comprising a chain secured to a movable member, a rotatable shaft, provided with a plurality of winding drums, a chain secured to a movable member and adapted to be wound upon one of said drums, a second rotatable shaft provided with a winding drum, and a chain one end of which is adapted to be wound upon one of said drums, and a chain one end of which is adapted to be wound upon a drum upon said first named shaft; a piston operated by compressed air or the like, a rod connected with said piston and provided with a rack, and a gear wheel on said second named shaft adapted to engage with the said rack. 110

15. A dumping car, comprising running gear, end body members, a movable member suspended from the upper side of the car, a movable member secured to the lower part of the car near the side thereof, a movable member secured to the lower part of said car near the middle line thereof, a support- 125

ing leg for said last named movable member, a slideable channel iron adapted to support said supporting leg, and means adapted to move said channel iron, comprising a piston operated by compressed air, and devices operably connecting said piston with said channel iron.

16. A dumping car, comprising running gear, end body members, a movable member suspended from the upper side of the car, a movable member secured to the lower part of said car near the side thereof, a movable member secured to the lower part of said car near the middle line thereof, a supporting leg for said last named movable member, a slideable channel iron adapted to support said supporting leg and means adapted to slide said channel iron, comprising a piston operated by compressed air or the like, a rod connected with said piston, a roller operated by said rod, a lever projecting from said roller, a link pivoted in the outer end of said lever and a bell-crank lever having one arm pivoted to said link, and having the other arm operatively connected with said channel iron.

17. A dumping car comprising running gear, end body members, a movable member suspended from the upper side of the car, a movable member secured to the lower part of the car near the middle line, a movable

member secured to the lower part of the car near the side, and means for operating said movable members, comprising a chain secured to a movable member, a rotatable shaft provided with a winding drum, said chain secured to a movable member being adapted to be wound around said drum, a ratchet wheel on said rotatable shaft, and devices adapted to engage with or release said ratchet, comprising a lever, a locking device for said lever, a second lever pivotally mounted on said first named lever, said second lever being normally held in one position by a spring, a rod pivotally secured to one end of said second lever, a member provided with a projection, and slidably mounted on said first named lever, one end of said sliding member being pivotally attached to said rod, a bell-crank lever provided at one end with a notch adapted to engage with the projection on said sliding member, and a pawl pivotally secured to the other end of said bell-crank lever.

In witness whereof I have hereunto signed my name this 4th day of April, 1914, in the presence of two subscribing witnesses.

WILLIAM D. SKIDMORE.
